UNITED STATES PATENT OFFICE.

OLE HANSEN, OF WALNUT GROVE, CALIFORNIA.

FIRE-ESCAPE.

SPECIFICATION forming part of Letters Patent No. 336,713, dated February 23, 1886.

Application filed November 20, 1883. Serial No. 112,308. (No model.)

To all whom it may concern:

Be it known that I, OLE HANSEN, a citizen of the United States, residing at Walnut Grove, in the county of Sacramento and State 5 of California, have invented a new and useful Fire-Escape, of which the following is a specification.

My invention relates to improvements in fire-escapes in which folding ladders are employed and so constructed as to conform to the architecture of the building to which they are attached when the same are folded up and out of use.

My invention will be readily understood by 15 reference to the accompanying drawings, in which—

Figure 1 is a perspective elevation of a building with my improvement attached. Fig. 2 is a side elevation of a portion of the 20 ladder to show the side view of the brace which serves to keep the ladder from swinging or swaying sidewise, and is employed near the top or bottom of the ladder. Fig. 3 is a plan view of the same as that shown in 25 Fig. 2. Fig. 4 is a side elevation showing a portion of the ladder and partially raised as in the act of folding. Fig. 5 is a portion of the outer rail of the ladder to show the attachment of a projection conforming to a projection upon the house. Fig. 6 is a side elevation of a portion of the ladder, showing a pinion and segment attached as one mode of raising the same. Fig. 7 is a side elevation of portion of the ladder with a broken part of 30 the folding platform or window-step. Fig. 8 is a detail view of a window, showing the folding platform or window-step as it appears when the ladder is opened out, ready for use. Fig. 9 is a portion of the ladder-strip employed to attach the folding ladder to a house 35 already constructed. Fig. 10 is a vertical plan view showing a section of the same as that shown in Fig. 9.

The following is the construction of the 40 same: I form the ladder of metal, the outer rail, A, with a groove to receive the rounds of the ladder when folded up in the front wall of the building. I attach any suitable molding or other projection, B, (corresponding in form to the moldings and projections

on the front of the building, which is recessed to receive the ladder,) to the rail A. I form the rounds of the ladder of metal, and pivot one end in the rail A at C and the other end 5 at D in the inner strip or ladder-rail, E. I employ several different modes of operating the ladder, according to the construction and arrangement of the house. I raise and lower or open the same by the segment and pinion F and G. (Shown in Figs. 4 and 6.) I balance the weight of the outer rail, A, by the weight H. (Shown in Figs. 1 and 4.) I attach the bell I and arrange the arm or lever J to strike the same as the pulley K is revolved by the ladder-cord L, passing over it as the ladder opens out. I attach the platform L' under the windows and pivot it to work upon the same line or axis as the rounds of the ladder, so that when the ladder is opened out a platform wide enough to step out upon is just a little below the window-sill, connected with the ladder by the rails M and N, leaving a space at the end between the platform and the ladder to 60 pass down through. I employ the portable ladder-strip R with flanges S S to receive the rounds Z. I attach the strip R by means of the bolts V or similar attachment. I sometimes employ the lever or arm J to strike or set off any well-known coil-spring or other alarm, so as to make sufficient noise to alarm the whole house instantly, instead of employing the common bell, I.

The following is the operation of my fire-escape: When a fire is discovered, the segment F is operated by means of the pinion G, or any well-known device for throwing the ladder out and down until the outer rail, A, rests upon the ground and the rounds of the 70 ladder lie in a horizontal position. The platform L is in position to allow a person to step out upon the platform and descend the ladder between the arms M and N. The platform L serves as a firm brace to the ladder to 75 keep it from swaying sidewise; but I sometimes employ the braces X (shown in Figs. 2 and 3) for that purpose, near the top or bottom of the ladder, or at a point where it may be required and there is no platform L to steady it.

Having thus described my invention, what I claim, and desire to secure by Letters Patent, is—

The combination, with a building, of rounds pivoted thereto at their inner ends, the rail A, to which the rounds are pivoted at their outer ends, the projection B on rail A, the

weighted rope attached to the upper end of the rail A and passing over a pulley, the segmental rack F, and pinion G, substantially as set forth.

Witnesses: OLE HANSEN,
JOHN H. REDSTONE,
L. E. REDSTONE.
